ABSTRACT OF THE DISCLOSURE

A dispensing machine for successively delivering either bottled or canned beverages from a staggered stack arrangement in respective product columns and having structure for supporting the rear baffle of each column to permit shifting of the baffle from a bottle accommodating position to a shorter can location without the use of tools or necessity of dismantling components of the machine. When converting each column from bottle to can dispensing, baffle hangers normally stored on the back wall of the column are affixed to each upper baffle bracket in forwardly projecting relationship therefrom with each hanger having members projecting outwardly therefrom to present recesses for receiving the upper tabs of the baffle to support the latter while at the same time place a bias on the baffle to force the bottom part thereof toward the rear wall of the column. A W-shaped wire retainer pivotally mounted on each rear wall is selectively shiftable from an out-of-the-way position to a location engaging the baffle when supported by the hangers to maintain the baffle in an upright position.

This invention relates to a dispensing machine for successively delivering either bottled or canned beverages from a plurality of upright stacks thereof in staggered relationship for most efficient utilization of the storage capacity of the machine, and is especially directed to the provision of simple, inexpensive and readily convertible structure for supporting the rear baffle of each product column in a location forwardly of the normal disposition thereof for bottle vending, when it is desired to convert the machine to can vending form.

For many years, prepackaged beverages have for the most part been vended in bottled form because of the ease with which the containers could be handled in the machine, the relative uniformity between the bottles, especially of the same type and size, and the low cost of the glass bottles because of their reuse over and over. Furthermore, bottlers have for the most part been set up to refill glass bottles with automatic equipment and considerable capital investment has been made in filling and capping machines.

In recent years though, as labor costs in particular have outdistanced the costs of beverages and the containers therefor of the throw-away type, the ratio of bottle to non-bottle dispensing machines has changed dramatically. The trend in this respect is attributable to advancements in the throwaway containers which have been developed permitting the opening thereof without

2

accessory openers. This is especially true insofar as metal containers are concerned with the advent of cans made entirely or partially of aluminum and having structure in the top thereof permitting manual opening without a key.

5 The swing toward can venders has required manufacturers to develop and offer machines for dispensing cans and problems have arisen in this respect because of the difference in length between bottles and cans. Since the costs in connection with dispensing machines themselves 10 have risen, competition has made it necessary to produce a single machine which is capable of dispensing either bottles or cans at the selection of the operator. However, because of the frequency of change of location of the machines and the desirability of varying the nature of the 15 product dispensed at any one location, it is necessary that the machine be readily convertible from can to bottle dispensing, or vice versa, in a minimum of time and preferably without the use of hand tools or the necessity 20 of dismantling various components of the machine.

It is therefore the primary object of the present invention to provide a dispensing machine for successively 25 delivering either bottled or canned beverages from a staggered stack arrangement in respective product columns and having structure for supporting the rear baffle of each column in a manner to permit shifting of the baffle from a bottle accommodating position to a location adapting the column for receiving shorter cans without the use of tools or of dismantling various components 30 of the machine.

A typical staggered stack vending machine for dispensing either bottled or canned beverages is illustrated in Patent No. 3,231,129. However, as shown in this patent, the mechanism is not readily convertible back and forth from bottles to cans or cans to bottles. This is particularly true as to the rear wall structure of each product 35 column which must necessarily abut the ends of the containers to maintain the same in the required relationship to the article release devices underlying the staggered stacks of bottles or cans. Since bottles are of substantially greater length than cans, it is necessary that the rear wall be positioned in one location for bottles and then moved forwardly therefrom for cans. It has been conventional for some time to provide a shiftable baffle adjacent the rear part of each column and carried by a hanger having a series of slots therein for receiving opposed 40 tabs on the baffle, so that the disposition thereof front to rear of a corresponding column may be altered depending on the length of a particular bottle.

However, it has not been practical to extend the length of these slotted brackets so that the baffle could be moved forwardly a sufficient distance to accomodate cans in the column, because the brackets would then interfere with the vending of bottles from the machine.

55 It is therefore a very important object of the invention to provide baffle supporting structure for the product columns of a staggered stack dispensing machine which includes hangers that may be stored on the rear wall of a respective column when the machine is set up for bottle delivery, but which can be mounted on the baffle brackets carried by opposed side walls of the respective column and extending forwardly from the brackets in disposition to re-

ceive and support the baffle in a can accommodating location. In this respect, it is another important object of the invention to provide hangers described having projecting member thereon located in disposition to define recesses for receiving tabs at the upper end of the baffle to suspend the latter from the hangers while at the same time providing a bias on the baffle so as to force the lower part thereof rearwardly of the column and obviate the necessity of providing supports at the lower extremity of each baffle.

A still further object of the invention is to provide hangers for supporting the baffle when it is desired to convert the dispensing machine to can operation, that are of such nature that only a single type of hanger need be fabricated for use on either side wall of the corresponding product column, thereby lowering the overall cost of the conversion assembly.

Another important object of the invention is to provide an assembly for supporting each column baffle which includes a substantially W-shaped wire pivotally mounted on the rear wall in disposition such that it may be swung downwardly into blocking relationship to the lower part of the baffle when the latter is suspended from the hangers previously described, so as to maintain the baffle in an upright position.

In the drawings:

FIGURE 1 is a fragmentary, vertical cross-sectional view with parts being broken away for clarity, of one column of a staggered stack dispensing machine showing the support assembly for suspending the column baffle in disposition for delivery of cans from the machine;

FIG. 2 is a vertical cross-sectional, fragmentary view of the top part of the structure illustrated in FIG. 1, and looking toward the rear of the column;

FIG. 3 is a fragmentary, horizontal cross-sectional view taken substantially on line 3-3 of FIG. 1 and looking downwardly in the direction of the arrow;

FIG. 4 is a fragmentary, vertical cross-sectional view similar to FIG. 2, but showing the lower part of the column and illustrating the disposition of the wire blocking element in its stowed position; and

FIG. 5 is a longitudinal sectional view through one of the hangers illustrated at the upper part of FIG. 1.

As is apparent from U.S. Patent No. 3,231,129, staggered stack vending machines normally have a series of product receiving columns to provide product selectivity and with the delivery of articles from alternate stacks of each column being controlled by release mechanism at the lower end of each column. The release mechanism has not been shown herein to simplify the drawings and in view of the fact that the control mechanism forms no part of the present invention.

For ease of construction, a staggered stack dispensing machine is normally provided with a prefabricated assembly defining a series of product columns, which is then inserted as a unit into the cabinet of the machine. The rear wall 10 of this prefabricated column assembly is illustrated in the drawings along with a pair of side walls 12 and 14 cooperable therewith to define one column 16 of the machine. Side walls 12 and 14 are spaced apart a distance somewhat less than twice the diameter of articles to be delivered from the machine so that such articles are maintained in staggered, stacked relationship between the side walls. As previously indicated, and referring to FIG. 3, the article release mechanism associated with column 16 is not shown.

Each of the side walls 12 and 14 is conventionally provided with upper and lower baffle brackets 18 and 20 which are generally U-shaped in configuration and have outer flanges 22 and 24 which lie flatly against the face of the side walls 12 and 14 and are secured thereto by fasteners passing through flanges 22. The central U-shaped section 26 of upper bracket 18 has a series of parallel, upright slots 28 therein for receiving corresponding upper tabs 30 of the baffle 32 while the central U-section 34 of lower brackets 20 has a series of parallel, upright slots

36 therein which extend only partially through the section to receive a flange portion of baffle 32 in supporting relationship to the latter.

It is to be understood that brackets 18 and 20 serve to support the baffle 32 in disposition to accommodate bottles in column 16 and that the baffle is adjusted longitudinally of respective brackets 18 and 20 depending upon the length of the bottles to be dispensed from a particular column. Thus, bottles of different lengths may be dispensed from the same machine.

When it is desired to convert the machine from bottle dispensing to can operation, insofar as the disposition of baffle 32 is concerned, the change can be made readily and simply without the use of hand tools or dismantling of various components of the machine. Hangers broadly designated 38 are affixed to the upper hanger brackets 18, while a blocking wire element broadly enumerated 40 is swung downwardly from the stored position thereof on rear wall 10 as shown in FIG. 4 to the operative location thereof illustrated in FIG. 1.

Each hanger 38 is of identical construction so as to permit use thereof on either of the side walls 12 and 14 and as a consequence minimizing the cost of producing the hangers. In addition, the machine operator need not concern himself with maintaining a stock of right- and left-hand hangers for various machines.

As is best shown in FIG. 1 and 5, each of the hangers 38 has a generally U-shaped mounting section 42 which is adapted to be telescoped into the U-shaped section 26 of a corresponding bracket 18. Section 42 is integral with a generally V-shaped body section 44 having opposed side margins 46 and 48 which diverge in a direction away from mounting section 42. Margins 46 and 48 are turned out in a direction away from body section 44 to increase the rigidity of the hanger.

A central part of body section 44 is turned out from the plane thereof as illustrated in FIGS. 1 and 5 to present an elongated member 50 which is disposed intermediate margins 46 and 48 and in perpendicular relationship to a bisector between such margins. A pair of end members 52 and 54, integral with body section 44 and turned out of the main plane thereof in the same direction as member 50, are spaced from the latter and located at an angle with respect to the longitudinal length of member 50.

The members 52 and 54 are of the same height as member 50, and are located at acute angles with respect to the longitudinal length of members 50 such that the outer ends of members 52 and 54 extend at least as far as extensions of the longitudinal axis of member 50. The hanger 38 is provided with the two members 52 and 54 arranged in the same relationship to member 50, so that a single hanger may be fabricated for use on either of the side walls 12 or 14 of column 16. However, it is to be noted that the members 52 and 54 are both located in critical

relationship with respect to member 50 so as to define a recess for receiving corresponding tabs 30 therebetween as shown in FIG. 1. The angular disposition of the members 52 and 54 relative to the longitudinal length of member 50 is important so as to provide a bias on baffle 32 in a counterclockwise direction viewing FIG. 1, so that the lower extremity of the baffle is forced toward rear wall 10.

A spring retainer 56 fastened to the surface of body section 44 normally facing away from the side wall 12 or 14, has an outwardly bent integral leg 58 on the end thereof remote from the fastener for disposition in the first slot 28 of bracket 18 as shown in FIG. 1. Outwardly bent integral projections 60 from body section 44 on opposite sides of retainer 56 maintain the same parallel with longitudinal lengths of mounting section 42. The major length of retainer 56 is bent outwardly at a sufficient angle as shown in FIG. 5 to cause leg 58 to be retained within the first slot 28 until force is applied to the central, outwardly bent segment of retainer 56 to permit leg 58 to clear the channel-shaped section 26 of bracket 18.

It is also preferred that mounting section 42 of hanger 38 be provided with a double keyhole slot 62 therein to permit storing of the hangers on a screw 64 carried by ear wall 10 until such time as the hangers are mounted on brackets 18 as illustrated in FIG. 1.

The generally W-shaped blocking element 40 has a pair of opposed, generally J-shaped legs 66 and 68 which are received within corresponding openings 70 in rear wall 10 so that the element 40 may be swung from a normally stored position as illustrated in FIG. 4, to an operative location as shown in FIG. 1. The outer straight segments 72 and 74 of element 40 integral with the elongated portions of legs 66 and 68 are normally positioned to lie against corresponding side walls 12 and 14 in generally parallelism therewith, and are adapted to be received within generally Z-shaped brackets 76 which thereby have outwardly projecting intermediate sections 78 which define shoulders for segments 72 and 74. Brackets 76 are normally provided on side walls 12 and 14 for holding spacer plates of the type shown in U.S. Patent No. Re. 25,521. These spacer plates are used only for bottle vending operations and are removed when the machine is converted to can dispensing.

The baffle 32 is shown in the figures in the disposition thereof wherein column 16 is adapted to receive cans, and it is to be appreciated that upon removal of the hangers 38 and swinging of blocking element 40 back to the stored position thereof as shown in FIG. 4, the baffle 32 is reversed so that the neck divider part 80 thereof faces to the left viewing FIG. 3 rather than to the right as shown.

In order to provide clearance for the part 80, the central section 82 of element 40 is of generally V-shaped configuration with the outer, aligned leg portions 84 thereof integral with segments 72 and 74 respectively, extending transversely of column 16 directly in front of the brackets 76. In this manner, the leg portions 84 serve as stops for baffle 32 and the extent of rearward movement of element 40 is limited by brackets 76. The element 40 thereby serves to maintain baffle 32 in a truly vertical position and it is only necessary to provide suspension structure for baffle 32 at the uppermost end thereof.

It can now be appreciated that conversion of the dispensing machine from a bottle operation wherein the baffle 32 is carried by brackets 20 and maintained in a true vertical position by brackets 18, to a can function wherein it is necessary to reverse the baffle 32 and move the same forwardly of brackets 18 and 20, can be effected readily, in a minimum of time and without dismantling any of the components of the machine. The conversion steps involve nothing more than removing baffle 32, inserting hangers 38 in brackets 18, followed by swinging of element 40 down into the generally horizontal position thereof, and reinsertion of baffle 32 in column 16 in the disposition thereof illustrated in FIG. 3.

Having thus described the invention, what is claimed as new and desired to be secured by Letters Patent is:

1. In a machine for dispensing articles of either a first length or a shorter second length from an upright column adapted to receive a pair of stacks of the articles in staggered relationship and provided with a rear baffle and bracket means at the upper and lower ends of the column adjacent the rear part thereof for removably receiving the baffle to maintain the latter in a rear position and thus adapt the column for receiving articles of said first length, the combination with said column, the bracket means thereon, and said rear baffle of structure for receiving the baffle to maintain the latter in a forward location and thus adapt the column for receiving articles of said second length, said structure comprising:

extension means on the upper part of the column and projecting forwardly from the upper bracket means for receiving said baffle to support the latter in said location thereof, said extension means having components thereon engageable with said baffle for bias-

ing the lower end thereof toward the rear part of the column; and

blocking means on the lower part of the column engageable with the baffle in said location thereof to maintain the baffle in generally upright disposition against said bias thereon.

2. A machine as set forth in claim 1 wherein said extension means comprises a pair of hangers removably mounted on and extending forwardly from opposed upper bracket means on the columns.

3. A machine as set forth in claim 2 wherein the upper bracket means are configured and positioned to present generally horizontal channels open at least at the ends thereof facing forwardly of the column and wherein the extension hangers have leg sections removably telescoped into the channels of respective bracket means.

4. A machine as set forth in claim 3 wherein each of said extension hangers is provided with a V-shaped planar body section integral with the leg section thereof at the apex portion of the body section, there being a first elongated planar member projecting from one face of the body section remote from said leg section and located intermediate the side margins thereof which converge as said leg section thereof is approached, said first member being positioned with the longitudinal axis thereof in perpendicular relationship to a bisector between said side margins, and a pair of second elongated planar members projecting from said face of the body section on opposite sides of said first member longitudinally thereof, each of said second members extending inwardly toward said bisector from the outer extremities of said side margins of the body, located at an acute angle with respect to the longitudinal axis of the first member, and each terminating short of the respective adjacent extremity of said first member, the outer opposed ends of each of the second members extending at least as far as an extension of the longitudinal axis of said first member whereby the hangers may be used interchangeably on opposite sidewalls of the column.

5. A machine as set forth in claim 3 wherein the upper bracket means each have at least one upright slot therein for receiving a part of the baffle therein, and wherein the extension hangers each have a spring stop thereon releasably engageable with respective bracket means within said slots therein for securing the hangers to said bracket means and thereby the column.

6. A machine as set forth in claim 2 wherein the baffle has opposed outwardly extending tabs on the margins thereof located to be received in the bracket means on the column when the baffle is in said position thereof, and wherein each of the extension hangers is provided with members thereon presenting a recess for receiving corresponding upper tabs on the baffle.

7. A machine as set forth in claim 6 wherein each of said extension hangers is provided with a normally upright, elongated first tab engaging member and a second elongated tab engaging member spaced from the first member, located at an angle with respect to the longitudinal axis of such first member to form a recess therebetween for a respective baffle tab.

8. A machine as set forth in claim 6 wherein each of said extension hangers is provided with a normally upright elongated first tab engaging member and a pair of elongated second members disposed to engage a tab and spaced from one another as well as from the first member, said second members being on opposite sides of the first member longitudinally thereof and located at acute angles with respect to the longitudinal axis of said first member to form a recess between each second member and the first member for receiving a baffle tab therein.

9. A machine as set forth in claim 1 wherein said column is provided with a rear wall and said blocking means is pivotally mounted on the rear wall for movement from a stowed position substantially against the wall

to an operative blocking position extending forwardly from said rear wall.

10. A machine as set forth in claim 9 wherein said blocking means comprises a generally W-shaped element with the free ends thereof being pivotally received in the rear wall of the column.

11. A machine as set forth in claim 10 wherein is provided shoulder means on opposite sides of the column positioned to receive and support said element when the latter is shifted to the baffle blocking position thereof.
